UNITED STATES PATENT OFFICE.

WILLIAM JACKSON, OF ALLEGHENY, PENNSYLVANIA, ASSIGNOR TO JAMES MCCLURG, OF SAME PLACE.

MACHINE FOR ARRANGING CRACKERS.

SPECIFICATION forming part of Letters Patent No. 339,656, dated April 13, 1886.

Application filed January 5, 1886. Serial No. 187,728. (No model.)

To all whom it may concern:

Be it known that I, WILLIAM JACKSON, a citizen of the United States, residing at Allegheny, in the county of Allegheny and State of Pennsylvania, have invented new and useful Improvements in Machines for Arranging Crackers, &c., of which the following is a specification, reference being had to the accompanying drawings.

10 My invention relates to improvements in machines for arranging crackers, ginger-snaps, and like articles for packing; and the novelty consists in the peculiar construction and combination of parts, substantially as hereinafter 15 fully set forth, and specifically pointed out in the claims.

The invention is especially designed as an improvement in that class of machines shown in the patent to James McClurg, No. 326,769, 20 dated September 22, 1885; and it has, primarily, for its object to provide means whereby the crackers and like articles are automatically arranged, so that they can be conveniently grasped by the operator for packing; 25 to provide means whereby the rate at which the crackers are fed to the conveying and arranging devices can be conveniently regulated; and to combine simplicity, strength, and durability of construction with thorough effectiveness of operation.

In the accompanying drawings, Figure 1 is a side elevation of my improved machine. Fig. 2 is a plan view, and Fig. 3 is a vertical longitudinal section on the line $x-x$ of Fig. 2. 35 Fig. 4 is a view of one form of a removable delivery-spout.

Referring to the drawings, in which like letters of reference indicate corresponding parts in all the figures, A designates the frame of 40 the machine, upon which is supported a hopper, B, an inclined conducting-spout, C, and a receiving-tray, D, the peculiar construction and arrangement of which I will now proceed to describe. The hopper B is made curved or 45 semicircular in cross-section, and has its rear end preferably closed, as by a wall, b, and said hopper is supported above the bed or table of the frame by means of upright bars B' B'', arranged at the front and rear ends thereof. The 50 upper and lower ends of these supporting-bars are pivotally connected to lugs b' of the hop-

per, arranged at or near the middle thereof, and to lugs b'' of the table of the frame, as shown in Figs. 1 and 3 of the drawings.

The rear supporting-bar, B'', is made in two 55 sections, each of which is provided with a series of apertures, b'', which register or coincide and receive a pin, b', and by means of these apertured sections of the rear supporting-bar the rear end of the hopper can be elevated above or brought into the plane of the 60 front discharge end of said hopper, thus providing means for regulating the rate of feed of the crackers or other like articles contained in the said hopper.

To properly feed or discharge the crackers, it is necessary that the hopper should be given a slight shaking motion, and in the drawings I have shown my preferred form of mechanism for giving the hopper an oscillating or 70 shaking motion; but I would have it understood that I do not desire to limit myself to the particular form of devices shown for the purpose hereinbefore mentioned.

G designates a shaft journaled in proper 75 bearings or boxes, g, secured upon the table or bed of the frame A, said shaft having a pulley, G', driven by a belt, G'', from any suitable motor or power, and a crank, h, with which connects a rod or arm, h', and communicates the motion thereof to the front upright or standard, B', said upright being slotted longitudinally, as at i, and receiving a wrist-pin, i', of the forward end of the connecting-rod h'. It will be seen that when motion is applied to the pulley G' by the belt G'' 85 the crank-shaft G will rotate in its bearings, and the motion of said shaft will be transmitted to the front upright, B', and the hopper B by means of the connecting-rod h'. 90

The conducting and arranging tube C is made cone or funnel shaped--that is to say, it is made larger at its upper rear end than at its lower front end. The conducting-tube is made in two sections, C' C'', which are detachably connected together by hooks e or other suitable fastening devices. The upper section, C', of the casing is pivotally connected at its lower end to the front end of the vibrating hopper, and the upper end of the section C'' 95 enters or incloses the lower end of the section C', to which it is detachably connected.

The sections C' C² are made cone-shaped, and the upper end of the section C' has a bent portion, c', through which the crackers pass on their way to the delivery-spout. The lower end of the section C² of the spout has a bent, inclined, or angular foot, c², that rests and moves upon the front end of a curved receiving-tray. The lower section, C², of the delivery-spout is thus detachably connected to the upper section, and the lower section is made of different sizes and shapes in cross-section to properly arrange and deliver crackers of different designs, a number of these lower sections of the delivery-spout being provided, which interchangeably connect with the upper section. The lower section may be made circular, square, elliptical, rectangular, or of other form in cross-section to properly arrange crackers of that shape, and they are made of different diameters to receive and deliver crackers of the size to which the lower section is adapted.

The conducting-tube is arranged in an inclined position to properly conduct the crackers to the receiving-tray D, which is supported upon the table of the frame A, and the tray is made semicircular or of other form in cross-section to correspond with the shape of the articles fed to the tray by the arranging and delivery tube.

The conducting-tube C partakes of the motion of the vibrating hopper, as it is pivotally connected thereto, and the angular foot c² of the tube slides or moves in the rear end of the receiving-tray, the angular foot also serving to support the delivery-tube in proper position.

The operation of my invention is as follows: A section, C², of the conducting and arranging tube of the proper shape and size in cross-section corresponding to the shape and size of the crackers to be arranged, is connected to the section C' of the said tube, and the crackers are placed in the vibrating hopper in a heap by hand or poured upon a box or other like receptacle. Motion is now communicated to the crank-shaft to reciprocate the hopper, and the crackers are thus forced into the tube, care being taken to feed them slowly at first. The first crackers that pass into the conducting-tube will lodge in the lower bent end thereof, which corresponds in shape and size to the crackers, and the crackers that are successively fed to the tube will lodge against the crackers that are first stopped in the tube and against one another. As the motions of the hopper still continue, the crackers are fed into the tube, and the superimposed weight of the crackers at the upper end of the tube on the crackers that first entered the tube, and which are held at the lower end thereof, will cause the crackers at the lower end to assume an upright or approximately vertical position, in order to enable them to pass through the angular foot of the section C² and into the tray. The crackers are thus automatically arranged in an upright or approximately vertical posi-

tion and pass into the receiving-tray in that position, from whence they are removed at the open end, the crackers being arranged so that they can be easily and readily grasped and removed by the hand of the operator for packing them in boxes or other receptacles.

I do not desire to limit myself to the exact details of construction and form and proportion of parts herein shown and described as an embodiment of my invention, as I am aware that many changes therein may be made without departing from the principle of my invention.

The receiving-tray D is preferably made circular in cross-section, and provided with a longitudinal slot, d, at the upper portion of its periphery, so that the operator can insert his thumb or fingers in the slot to move the crackers forward and out upon a flat table.

A number or series of hoppers, together with their conducting-tubes and receiving-trays, may be provided, as is obvious.

I am aware that it is not new to provide a machine for drying grain, which comprises a frame, threaded rods having adjustable nuts supported and adjustable in the frame, a heated pan to which the grain is fed to be dried, and pivoted links intermediate of the pan and rods for adjustably suspending the same, and I do not claim such devices.

Having thus described my invention, what I claim as new, and desire to secure by Letters Patent, is—

1. In a machine for arranging crackers and like articles for packing, the combination of a supporting-frame, a vibrating hopper mounted thereon and movable throughout its entire area, a movable conducting and arranging tube connected to the hopper to receive the crackers therefrom, and a receiving-tray arranged in juxtaposition to the free end of the conducting-tube, substantially as described.

2. In a machine for arranging crackers and like articles for packing, the combination of a supporting-frame, a vibrating hopper supported thereon, a conducting-tube connected to the hopper and partaking of the motion thereof, and a tray for receiving the crackers and the like from the tube, substantially as described.

3. In a machine for arranging crackers and like articles for packing, the combination of a frame, a vibrating hopper mounted thereon, a conducting-tube connected to and partaking of the motion of the hopper, and provided with a section having a shape in cross-section corresponding to the shape of the crackers passing through the same, and a receiving-tray, substantially as described.

4. In a machine for arranging crackers and like articles for packing, the combination of the following elements, namely: a supporting-frame, a vibrating hopper mounted thereon, suitable mechanism for actuating said hopper, an inclined conical conducting-tube pivotally connected to the hopper, a tube-section of proper form connected to one end of the con-

ducting-tube, and a suitable tray in communication with the tube-section, substantially as described.

5. In a machine for arranging crackers and like articles for packing, the combination of a frame, a vibrating hopper mounted thereon and adjustable vertically at one end to vary the inclination thereof, a conducting-tube pivotally connected to the hopper, and a receiving-tray, substantially as described. 30

6. In a machine for arranging crackers and like articles for packing, the combination of a frame, a longitudinally-vibrating hopper, supporting-uprights for the hopper pivotally connected thereto and to the frame, the rear upright being vertically adjustable to vary the inclination of the hopper, a conducting-tube connected to and partaking of the motion of the hopper, and a receiving-tray, substantially as described. 35

7. In a machine for arranging crackers and like articles for packing, the combination of the following elements, namely: a main supporting-frame, a vibrating hopper, uprights pivotally connected to the hopper and frame,

a crank-shaft having a pulley and belt, a rod connecting the crank-shaft with one of the hopper-supporting uprights, a conical conducting-tube pivotally connected to the hopper and having an angular discharge-foot, and 30 a receiving-tray in communication with the tube, all arranged and combined substantially as described.

8. The combination of a vibrating hopper, a receiving-tray, and a sectional conducting-tube, substantially as described. 35

9. The combination of a movable hopper, a receiving-tray, and a sectional conducting and arranging tube, the lower section of said tube being detachably connected to the upper section and interchangeable with lower tube-sections of different sizes or shapes, substantially as described. 40

In testimony that I claim the foregoing as my own I have hereto affixed my signature 45 in presence of two witnesses.

WILLIAM JACKSON.
